TOOTH MOLD

Carl E. Becker, Camden, N. J.

Application May 18, 1931. Serial No. 538,370

3 Claims. (Cl. 18—42)

This invention relates to molds of the type employed in the manufacture of artificial teeth, and an object thereof resides in the provision of a simple and improved mold so designed as to permit of the rapid production of perfectly formed teeth and wherein the mold consists of easily assembled separable sections which may be readily united to produce a composite mold having registering depressions or pockets for the reception of the ceramic tooth forming materials and wherein the exterior sides of the assembled mold are shaped so that the mold may be received within a press adapted to hold the sections of the mold in assembled relationship, to apply pressure to the tooth forming materials contained therein and to permit of the drying of the materials while in the press by the application of heat.

It is another object of the invention to provide a mold of this character comprising a drag composed of a pair of outer sections and a center section, said center section having its side walls provided with a plurality of pockets or cavities of tooth-like form adapted to be brought into registering relationship with corresponding pockets or cavities formed on the inner walls of the outer sections, and wherein provision is made for assembling the sections of the drag in proper relative registration to insure accurate registration of the cavities and to prevent reversal in position of the center section.

It is a further object of the invention to provide a tooth mold of this type whereby through the medium of the center section of the drag, two or more rows of teeth may be produced in a single mold, and wherein the cope section of the mold comprises a single unitary member having pockets formed in its under surface arranged in parallel rows to register with the pockets or cavities provided in the several sections of the drag.

It is another object of the invention to form the exterior surfaces of the assembled mold in inclined planes whereby when the mold is positioned in a drying press and clamped between the stationary base and movable members of the press, several sections of the mold will be forced together and rigidly retained in proper assembled relationship.

It is another object of the invention to provide the exterior surfaces of the molds with heat conducting grooves or channels, whereby during the pressing operation the molds may be heated and gas uniformly circulated thereabout to secure the desired drying of the teeth being formed therein.

With these and other objects in view, which will appear as the description proceeds, the invention consists in the novel features of construction, combinations of elements and arrangement of parts hereinafter to be more fully described and pointed out in the appended claims.

Figure 1 is a perspective view of the cope of a tooth mold formed in accordance with the present invention.

Figure 2 is a perspective view showing in separated relationship the several sections of the drag of my improved mold.

Figure 3 is a transverse sectional view through the assembled mold when positioned in a drying press.

Referring more particularly to the drawing, the numeral 1 designates the mold in its entirety. The mold comprises a cope which is designated generally by the numeral 2 and a drag correspondingly designated by the numeral 3. The drag comprises a pair of outer sections 4—4 and a center section 5. These sections are preferably formed from a non-corrosive metal which when cast presents smooth unroughened surfaces. Alloys containing brass or bronze may be used in this capacity.

The center section 5 consists of a longitudinally extending bar having flat parallel vertical sides indicated at 6. These side surfaces have formed therein, during the process of producing the bar 5, a plurality of pockets or cavities 6a shaped in accordance with the formation of portions of human teeth and disposed on both sides of the center bar in parallel order and communicating openly with the upper edge of the center bar. Similarly, the outer sections 4 are each formed to include a flat inner vertical surface 7 which closely engages and registers with the side surfaces 6 of the center section or bar. The surfaces 7 are likewise formed with pockets or cavities 8 in the upper portions thereof which exactly register with the marginal portions of the pockets 6a provided in the center bar.

To insure this registration the center bar has its ends on one side provided with short shouldered recesses 9, while the opposite sides of the ends of the bar 5 are formed with what may be termed "long" recesses 10. Similarly, one of the sections 4 has its ends, which register with the recesses 9, provided with relatively short locking projections 11, while the complementary bar 4 has its end portions, which register with the recesses 10, provided with long shouldered projections 12. The ends of the bar 5 are substantially of dovetailed cross-sectional configuration.

whereas the main length of the bar is of substantially rectangular configuration, and the cross-sectional formation of the sections 4 is matched accordingly. The long and short recesses 9 and 10 in the ends of the bar 5 serve to insure proper registration between the recesses of said bar and the complementary recesses, cavities or pockets formed in the outer sections 4, thus preventing the reversing in position of the center bar and assuring its assembly in the completed mold in but one operating position. One of the drag sections 4 may be provided with transversely extending pins 13 contiguous to the ends thereof, which pins pass through openings 14 formed in the ends of the center bar and into sockets 15 formed in the other of the sections 4, a feature which further secures the necessary high degree of accuracy in the alignment and relative registration of the drag sections of the mold.

20 The cope section preferably comprises a single piece of metal which is of a width corresponding to the total width of the several sections of the drag when the latter are joined together. The cope section rests directly upon the upper surfaces of the drag sections and may be provided with one or more depending pins 16 which are received in sockets 17 formed in the outer sections 4 near the ends of the latter. The lower substantially horizontal surface of the cope is provided with a pair of spaced rows of longitudinally extending pockets or cavities 18, which register with the pockets and cavities 6a and 8 forming sections of the drag, whereby when the mold is in assembled order, as shown in Figure 3, the pockets or cavities in the several sections of the mold present closed cells of tooth formation into which the ceramic materials, used in the formation of artificial teeth, are pressed and forced into the desired tooth form. By this construction each mold is capable of producing two rows of artificial teeth, which is in contrast to the disclosures contained in my prior application Serial Number 279,226 filed May 21, 1928, of which this application is a continuation in part and in which prior application but one row of teeth can be produced in the mold therein set forth.

As shown in Figure 3, the drag and cope sections of the mold are provided with longitudinally extending exterior inclined surfaces 19 and these surfaces are further formed with a plurality of relatively intersecting grooves or channels 20. When the mold is used the cope section is removed from the drag sections while the latter are held in assembled relationship by any suitable means. The plastic ceramic materials may then be placed in the pockets 6a and 8 of the drag and likewise the plastic ceramic material may be placed in the pockets 18 of the cope. The cope is then placed on the drag with the pins 16 thereof fitting in the sockets 17. The entire assembled mold is then positioned between the stationary and movable members 21 and 22 of the drying press. These members 21 and 22 are formed with registering complementary grooves 23 having inclined walls corresponding to the inclination of the surfaces 19. Then the movable member is forced into pressure engagement with the cope section, producing corresponding pressure on the drag with the result that the press established forces are directed inwardly toward the center of the assembled mold from all sides, thereby holding the mold rigidly assembled, preventing relative movement between the sections thereof and applying requisite pressures to the

tooth forming material present in the mold cavities. During this pressing operation the molds are heated by means of fuel burners 24, arranged beneath the stationary member 21 and so disposed as to direct combustion gases upwardly and thence through and around the mold proper by passing through the grooves or channels 20. This produces a uniform heating of the mold and its contents to secure the desired drying and quick setting of the ceramic teeth contained in the mold. Following a proper period of pressing and heating the mold is removed from the press and the sections of the mold are allowed to fall apart which permits the teeth, which have received a primary heat treatment in the press, to be readily removed from the sections of the mold and transferred to other operations with but a minimum loss in time. The sections of the drag may then be reassembled and the operations above given repeated.

95 What is claimed is:

1. A mold for producing artificial teeth comprising a drag formed to include a center section and a pair of separable and adjoining outer sections, said center section having its vertical sides provided with rows of spaced tooth forming cavities, the outer sections of said drag having the vertical surfaces thereof which adjoin said center section formed with cavities arranged in registration with the cavities in the center section, 100 interengaging shouldered means formed between the center and outer sections of said mold for maintaining said center section in a predetermined order of assembly with said outer sections, and a single cope section formed to seat upon 110 the upper surfaces of said drag sections, said cope section possessing a width corresponding substantially to that of the total width of the assembled drag sections, the under surface of said cope section being provided with spaced 115 rows of cavities arranged to register with the cavities provided in the drag sections, said cavities being relatively spaced and non-communicating when said mold sections are in assembled order.

120 2. A mold for producing artificial teeth comprising a drag formed to include a center bar and a pair of separable adjoining outer bars, said center bar having its opposite sides provided with rows of tooth forming cavities, the outer bars 125 of said drag having the surfaces thereof which adjoin the center bar formed with cavities arranged to register with the corresponding cavities in the center bar, shouldered interengaging means formed between the center and outer bars 130 of said drag to limit said bars to a single predetermined order of assembly, a single cope bar seated upon the upper surfaces of the drag bars, said cope bar being of a width substantially corresponding to the total width of the assembled 135 drag bars and of approximately the same length as each of said latter bars, the under surface of said cope bar being provided with spaced rows of cavities arranged to register with the cavities provided in the drag bars, and means for obtaining predetermined registration in assembly between said cope bar and said drag bars.

140 3. A mold for producing artificial teeth comprising a drag formed to include a center section and a pair of separable and adjoining outer sections, said center section having its vertical sides provided with rows of spaced tooth forming cavities, the outer sections of said drag having the vertical surfaces thereof which adjoin said center 145

section formed with cavities arranged in registration with the cavities in the center section, interengaging shouldered means formed between the center and outer sections of said mold for maintaining said center section in a predetermined order of assembly with said outer section, and a single cope section formed to seat upon the upper surfaces of said drag sections, the under

surface of the cope section being provided with spaced rows of cavities arranged to register with the cavities provided in the drag sections, said cavities being relatively spaced and non-communicating when said mold sections are in assembled order. 80
